[57] CLAIM

The ornamental design for a wall mirror, as shown and described.

DESCRIPTION

FIG. 1 is a front perspective view of a wall mirror showing my new design;

FIG. 2 is a right side elevational view thereof;

FIG. 3 is a front elevational view thereof;

FIG. 4 is a rear elevational view thereof;

FIG. 5 is a top plan view thereof; and,

FIG. 6 is a bottom plan view thereof.

The surface texture has been shown fragmentarily for ease of illustration.
